[57] CLAIM

The ornamental design for a table, as shown and described.

DESCRIPTION

FIG. 1 is a top plan view of a table showing my design; FIG. 2 is a side elevational view;

FIG. 3 is a bottom plan view;

FIG. 4 is a perspective view taken from above and wherein a portion of the top is broken away for convenience of illustration;

FIG. 5 is a sectional view taken along the line 5—5 of FIG. 2 and wherein a portion of the top has been omitted for convenience of illustration; and,

FIG. 6 is a sectional view taken along the line 6—6 of FIG. 4 and looking in the direction of the arrows thereof.

FIG. 1.

FIG. 3.

FIG. 4.

FIG.5.

FIG.6.
